United States Patent Office

Des. 209,286
Patented Nov. 21, 1967

209,286

MULTIFEATURED SUBSCRIBER TELEPHONE STAND

Claude A. R. Kagan, Hopewell Township, Mercer County, N.J., assignor to Western Electric Company, Incorporated, New York, N.Y., a corporation of New York

Filed Dec. 10, 1965, Ser. No. 141

Term of patent 3½ years

(Cl. D26—14)

FIG. 1

FIG. 2

FIG. 3

FIG. 4

FIGURE 1 is a front perspective view of a multifeatured subscriber telephone stand, showing my new design; FIGURE 2 is a rear perspective view of the multifeatured subscriber telephone stand as shown in FIGURE 1;

FIGURE 3 is a plan view of the multifeatured subscriber telephone stand as shown in FIGURE 1; and

FIGURE 4 is a side elevational view of the multifeatured subscriber telephone stand as shown in FIGURE 3.

The dominant features of the new design are shown in solid lines in the drawings. The bottom, not shown, is unornamented.

I claim:

The ornamental design for a multifeatured subscriber telephone stand, as shown and described.
